UNITED STATES PATENT OFFICE

133,200

DESIGN FOR A LAUNDRY STOVE

William G. Probst, Jr., Ottawa, Ill., assignor to
Knowles Foundry & Machine Co., Ottawa, Ill.,
a corporation of Illinois

Application July 5, 1940, Serial No. 93,443

Term of patent 3½ years

To all whom it may concern:

Be it known that I, William G. Probst, Jr., a citizen of the United States, residing at Ottawa, in the county of La Salle and State of Illinois, have invented a new, original, and ornamental Design for a Laundry Stove, of which the following is a specification, reference being had to the accompanying drawings, forming part thereof.

Figure 1 is a front perspective view of a laundry stove, showing my new design.

Figure 2 is a side view of the laundry stove shown in Figure 1, the opposite side having the same appearance.

Figure 3 is a view showing the back of the laundry stove shown in Figure 1.

I claim:

The original design for a laundry stove, as shown.
